UNITED STATES PATENT OFFICE.

ROBERT C. BROMLEY, OF PITTSBURG, PENNSYLVANIA, ASSIGNOR TO THE PITTSBURG VALVE AND MACHINE CO., LIMITED.

VALVE.

SPECIFICATION forming part of Letters Patent No. 593,411, dated November 9, 1897.

Application filed December 10, 1896. Serial No. 615,168. (No model.)

To all whom it may concern.

Be it known that I, ROBERT C. BROMLEY, a citizen of the United States, residing at Pittsburgh, in the county of Allegheny and State of Pennsylvania, have invented or discovered a new and useful Improvement in Valves, of which the following is a full, clear, and exact description, reference being had to the accompanying drawings, forming part of this application, in which—

Figure 1 is a central vertical sectional view of a valve made in accordance with my invention. Fig. 2 is a similar view showing the plug turned to register with the openings in the valve-casing. Fig. 3 is a cross-section on the line III III of Fig. 1. Fig. 4 is a sectional perspective view of the lower part of the plug. Fig. 5 is a perspective detail view of the temper-screw.

20 My invention consists of an improvement in valves, and relates more particularly to the means for limiting the throw or travel of the valve-plug and for setting it tightly to its seat, together with means for adjusting and 25 taking up the wear of such mechanism without removal of the plug or any of the parts.

Referring to the drawings, 2 is the valve-casing provided with suitable inlet and outlet ports and a central tapered seat 3. Within 30 the casing is the plug 4, tapered to correspond to the seat 3 and provided with the lateral opening 5, coinciding with the inlet and outlet ports when in an open position, as shown in Fig. 2, and adapted to close such ports 35 when turned at right angles, as in Fig. 1. An extended stem 6 projects upwardly through a suitable stuffing-box, forming a part of the valve-casing, in the bottom of which is placed a suitable gasket 7, while at the bottom the 40 plug is provided with an extended circular sleeve 8. The base of the valve-casing is flanged, and secured thereto by bolts is a lower head 9, in the center of which is an extended downwardly-projecting internally-screwed

45 threaded housing 10. A bolt 11, provided with a polygonal head 12, is screwed downwardly into the threaded housing 10, sufficient play being allowed so that when screwed down to about the bottom of the threaded cavity in 50 the housing the head will occupy the space within the sleeve 8, the internal diameter of which is sufficiently large to allow the plug 4

to be rotated without interference with the head of the bolt. In the central base of the plug and immediately above the space within 55 the sleeve 8 is a polygonal cavity 13, corresponding to the shape of the head 12 and slightly larger to permit of an easy fit thereon. An annular groove 14 is made in the upper face of the flange 9 to permit of a slightly- 60 downward movement of the plug, by which action the head of the bolt will be engaged by the polygonal cavity 13, when upon rotating the plug motion will be imparted to the screw 11 and it will be caused to rise upon its 65 threads until the head 12 will occupy the cavity 13, as shown in Fig. 1. Continued rotation of the plug will cause the head 12 to seat itself against the top of the cavity 13, resulting in an upward pressure upon the plug, 70 whereby it will be caused to seat itself against the seat 3 of the valve-casing, and by reason of the polygonal head and cavity the relation of the plug to the head 12 may be so adjusted as to cause the head in its upward travel to 75 bind against the base of the plug, seating it against the valve-seat and arresting its further movement, when the plug is turned to the closed position shown in Fig. 1, and backward movement of the plug will, by similarly 80 rotating the screw, cause it to travel downwardly and immediately relieve such pressure.

In order to hold the plug to its seat at all times with a moderate pressure, ports 14 are 85 made communicating with the central opening 5 and leading upwardly and downwardly, supplying pressure upon the shoulders 15 16 of the plug, the lower of which, by reason of its greater area, will receive a greater pres- 90 sure and such excess of pressure will serve to always keep the valve to its seat.

A packing-ring 17, interposed between the flanged base and head 9 and embracing the sleeve 8, makes a tight joint against leakage. 95

The operation of my device will be readily understood from the foregoing description, and the advantages of my construction will be appreciated by the skilled mechanic.

By permitting the plug to be disengaged 100 from the bolt and turned for one or more faces of the polygonal head without removing any of the parts the operation of setting and adjusting the plug to its seat so as to bind at the

termination of its movement is rendered comparatively simple and expedient.

Having described my invention, what I claim is—

- 5 1. A valve having a chambered tapered plug, a threaded screw mounted in a part of the valve-casing, and in engagement with the plug whereby rotation of the plug will rotate the screw and advance it toward or from the plug in line with its axial center, substantially as set forth.
- 10 2. A valve having a chambered tapered plug, a polygonally-headed screw mounted in a part of the valve-casing, and a similarly-shaped polygonal cavity in the plug for engagement with the head of the screw, substantially as set forth.
- 15 3. A valve comprising a casing having a tapered seat, a correspondingly-tapered plug, a polygonal cavity in the base of the plug, an extended sleeve beyond such cavity, and a polygonally-headed screw-threaded bolt mounted in a part of the valve-casing and adapted to be engaged by the cavity of the plug, substantially as set forth.
- 20 4. A valve comprising a casing having a ta-

peried seat, a correspondingly-tapered plug, a polygonal cavity in the base of the plug, an extended sleeve beyond such cavity, a flanged head comprising a part of the valve-casing provided with clearance-space for the extended sleeve, and a threaded socket, and a packing-ring surrounding the extended sleeve, substantially as set forth.

5. A valve comprising a casing having a tapered seat, a correspondingly-tapered plug, a polygonal cavity in the base of the plug, an extended sleeve beyond such cavity, a flanged head comprising a part of the valve-casing provided with clearance-space for the extended sleeve, and a threaded socket, a packing-ring surrounding the extended sleeve, and pressure-surfaces and chambers at each end of the plug with ports leading thereto from the central opening, substantially as set forth.

In testimony whereof I have hereunto set my hand this 2d day of October, 1896.

ROBERT C. BROMLEY.
